GOVERNING SYSTEM FOR A FUEL FEED DEVICE

Ulrich W. P. Anders, Stuttgart-Unterturkheim, Germany, assignor to Daimler-Benz Aktiengesellschaft, Stuttgart-Unterturkheim, Germany

Application July 23, 1954, Serial No. 445,353

Claims priority, application Germany July 25, 1953

17 Claims. (Cl. 123—140)

My invention relates to a governing system for a fuel feed device of an internal combustion engine and is particularly applicable to a fuel-injecting device of an engine in which gasoline is injected into an air charge for subsequent compression and ignition by a spark plug.

Engines of that type require that the ratio of mixture between air and gasoline be kept within very narrow limits. It is a prerequisite for a compliance with this requirement that the quantity of fuel injected for each reciprocation of the piston be proportional to the weight of the air charge sucked into the cylinder by the piston, such weight depending on both the atmospheric pressure and the temperature of the atmosphere.

It is the object of the present invention to provide a governing system for a fuel feed device of an internal combustion engine in which the quantity of the fuel fed per cylinder charge is controlled so as to secure the most favorable ratio of mixture, such control depending on the pressure and the temperature of the atmosphere.

More particularly, it is an object of the invention to provide a governing system for a fuel-injecting device in which the quantity of the fuel injected is subject to a primary control in dependence on the volume of the cylinder charge and to a secondary control in dependence on the temperature and the pressure of the air.

A further object of the invention is to provide an improved governing system for the purpose indicated which complies in a superior manner with the theoretical and practical requirements in which the secondary control depending on the pressure and temperature of the air charge will have a greater influence when the injecting device is set for injection of a larger quantity of fuel, and will have a smaller influence when the injecting device is set to inject a small quantity of fuel.

Further objects of my invention will appear from a detailed description of a number of preferred embodiments of the invention illustrated in the accompanying drawings, it being understood that such detailed description serves the purpose of illustration of the invention rather than that of restricting the same.

In the drawings,

Fig. 1 is an elevation partly in section of the novel control system, the diaphragm chamber illustrated therein being shown on an enlarged scale, the control system including a joining device comprised of a cam and a follower;

Fig. 2 is a view on an enlarged scale similar to Fig. 1 of some of the elements of the control system shown therein;

Fig. 3 is a partial section through the control system substantially along the broken line III—III of Fig. 1;

Fig. 4 is an elevation partly in section of another embodiment of the invention, the diaphragm chamber being shown on an enlarged scale;

Fig. 5 is a side view of the control system shown in Fig. 4 partly in section along the line V—V;

Fig. 6 is a view similar to that of Figs. 1 and 4 of a

2

modification of the control system in which the joining device comprises a linkage rather than a cam; and

Fig. 7 is a partial section of the control system shown in Fig. 6, such section being taken along the line VII—VII of Fig. 6.

Fig. 1 shows an internal combustion engine 10 equipped with a fuel-injecting device diagrammatically indicated at 11 adapted to intermittently inject gasoline into the cylinders of the engine for subsequent compression and ignition by spark plugs, the quantity of fuel injected at any time being determined by position of a control member 12 in the form of a horizontal rod movable in lengthwise direction. The intake manifold 13 of the engine is connected by a pipe 14 to a diaphragm chamber 15 mounted in stationary relationship to the engine 10 and closed by a diaphragm 16. The quantity of the air charges sucked by the reciprocating pistons into the cylinders of engine 10 is controlled by the orthodox throttle valve 17 adjustable by an accelerator pedal or the like. The vacuum produced in the intake manifold 13 when the throttle valve 17 is more or less closed is transferred by the pipe 14 to the diaphragm chamber 15. Therefore, the diaphragm 16 will at any time assume a position representative of the vacuum and, consequently, of the weight of the air charges. In the position shown, the throttle 17 is partly closed. The diaphragm 16 is subjected to the pressure of a spring 18 inserted between the bottom of chamber 15 and a member 19 fixed to the central portion of the diaphragm. When the throttle 17 is further opened the pressure prevailing in the intake manifold 13 and in the diaphragm chamber 15 will rise moving the diaphragm 16 in the direction of the arrow 20. When the throttle 17 is closed, however, the diaphragm will move in a direction opposite to that of arrow 20.

The novel governing system comprises the following basic elements:

(1) The control member 12 movable in axial direction to vary the quantity of fuel fed to the engine by the fuel-injecting device 11.

(2) A main actuating member constituted in the present embodiment by the diaphragm 16 which is responsive to any change of the weight of the combustion air fed into the internal combustion engine, it being understood that the weight of the air charge controlled by the throttle 17 will vary in proportion to the pressure prevailing in the intake manifold 13.

(3) A joining device which connects the control member 12 and the main actuating member 16 for the transfer of actuating motion from the actuating member 16 to the control member 12 in the axial direction of the latter, which direction hereinafter will be referred to as the first direction. In the embodiment shown, such joining device comprises a rod 21 fixed to the central portion of the diaphragm 16 and provided at its end with a laterally projecting pin 22, a slotted member 23 engaged by the pin, and a rod 24 connecting the slotted member 23 to the rod 12.

(4) A correction member, such as a pressure gauge 25 or a temperature-responsive thermostat diagrammatically indicated at 26, and

(5) Means connecting the correction member 25, or 26 respectively, to the joining device 21, 22, 23 for transfer of an adjusting motion from the correction member, such as 25, to the joining device in a second direction which extends transversely to the first direction, such means comprising in the present embodiment a two-armed lever 27 pivotally connected to rod 21 preferably at the free end thereof, a two-armed lever 28 journaled in a stationary bracket 29 and having one arm connected by a rod 30 to the pressure gauge 25, and

a link 31 which connects the other arm of lever 28 to one arm of lever 27.

In the embodiment shown, the other arm of lever 27 is connected by a link 32 to one arm of a bell crank 33 which is fulcrumed on a stationary bracket 34 and has its other arm connected by a link 35 to the thermostat 26 which is mounted at any suitable point so as to measure the temperature of the air sucked into the cylinders of the engine. The means described which connect the correction member or members to the joining device will transfer an adjusting motion from the correction member or members to the joining device in a second direction extending transversely to the arrow 20 to thereby effect a corrective adjustment of the control member 12 in addition to the actuating motion of the diaphragm 16. Thus, it will appear that when the temperature of the air sucked into the cylinders of the engine increases, links 35 and 32 will be moved in the direction of arrows 36 and 37 whereby lever 27 will be rocked upwardly about its right hand end lifting pin 22. Pin 22, however, is guided by link 21 along an arc about a point which substantially coincides with the center of the diaphragm 16. Therefore, pin 22 is movable substantially at right angles to link 21. As the slot 40 of the slotted member 23 is slightly inclined, pin 22 causes the slotted member 23 to be displaced in a direction away from the engine 10. The slotted member 23, in its turn, will displace link 24 and control member 12 in a direction opposite to the arrow 20 thus reducing the quantity of fuel injected. Such a reduction of the fuel feed corresponds to the reduction of the density of the combustion air caused by the rise of the temperature. A similar effect will be obtained when a reduction of the atmospheric pressure causes the pressure gauge 25 to expand and lever 28 to rock in clockwise direction whereby lever 27 will be rocked upwardly about its left hand end. It will be understood, of course, that both rocking motions of lever 27 will be superimposed upon each other when changes of the temperature and of the air pressure occur simultaneously.

The opposite corrective adjustment of control member 12 will occur upon a reduction of the temperature or an increase of the atmospheric pressure, as will be readily understood. In such event, pin 22 will be depressed moving control member 12 in the direction of arrow 20.

From the foregoing it will be understood that upward or downward adjustment of the joining device effects a corrective adjustment of the control member 12 in addition to the actuating motion accomplished by diaphragm 16. As will now be explained, such corrective adjustment caused by the up-and-down adjusting motion transferred to the joining device from the correction member 25 or 26 is variable by movement of the actuating member 16 in such a manner that, for a given movement of the correction member 25 or 26, positioning the control member 12 for a large fuel feed causes the corrective adjustment to be larger than positioning the control member 12 for a smaller fuel feed. This result is obtained by a pivotal movement of the slotted member 23. The latter is integral with a rod 37 which is journaled on a stationary bracket 38 by means of a pin 39. When the throttle 17 is closed causing diaphragm 16 to be sucked into the diaphragm chamber 15, the rod 21 will move in a direction away from the engine 10 pulling the slotted member 23 to the position shown in dotted lines at 23'. Bracket 38 and pin 39 are so located that now the slot 40 of slotted member 23 extends at right angles to the rod 21. As a result, the adjusting motion imparted to slotted member 23 by the correction member 25 or 26 will not impart any corrective adjustment to control member 12.

In the position shown, the engine is operating nearly at full power. When the throttle 17 is closed to reduce the power produced, the vacuum prevailing in the intake

manifold 13 and in the diaphragm chamber 15 increases. As a result, the diaphragm 16 moves opposite to the direction of arrow 20 thereby compressing spring 18. This actuating motion of the diaphragm 16 is transferred to the control member 12 through the elements 21, 22, 23 and 24 of the joining device; thus reducing the quantity of fuel injected. When this transfer of motion occurs, the rod 37 will rock about its pivot 39 whereby the angle A included between the slot 40 and a line 41 perpendicular to rod 21 will be reduced to the amount B; the slot 40 now assuming the position 40' shown in dash-dotted lines. As a result, a given increment of the adjusting motion imparted to pin 22 along slot 40 will produce a smaller increment of corrective adjustment of control member 12 than before when link 37 was in the position shown in full lines. When the throttle is fully closed the member 23 will be moved to the position 23' discussed above, its slot being in the position 40'. In this position the angle B has been further reduced to zero so that a vertical displacement of pin 22 does not affect the position of control member 12 in any way.

While angle A coordinated to the extreme full load condition of control member 12 is larger than angle B, it is still so small that the actuation of rod 21 by the diaphragm 16 will exert a negligible vertical force component only upon the pin 22. Therefore, the correction members 25 and 26 will not be subjected to exterior forces to any material appreciable extent.

In effect, the face 42 of slot 40 constitutes a cam and the pin 22 constitutes a follower which is held in permanent contact with the cam face 42 by the yoke portion 43 confining the slot 40. Obviously, any desired means may be substituted for such yoke portion 43 of member 23 for the purpose of holding the follower 22 in contact with the cam 42.

Viewed under this aspect, the slotted member 23 constitutes a cam which is mounted for bodily movement in the axial direction of control member 12, the link 37 constituting means for turning the cam 23 in response to the actuating motion of the diaphragm 16 to thereby vary the inclination of the cam face 42.

It will be noted that the links 31 and 32 extend substantially parallel to each other and to the link element 37 in a direction more or less transversely to the arrow 20, and that the two links 31 and 32 have a length substantially equal to the link element 37. This has the effect of reducing any relative displacement between the link member 23, 37 and the follower member 22 incidental to the actuating motion of the diaphragm 16 to a minimum.

In Figs. 4 and 5 there is illustrated an embodiment differing from that shown in Figs. 1, 2 and 3 by the structure of the means connecting the correction member to the joining device. In this embodiment, such means comprises a linkage in which both a thermostat 44 and a pressure-responsive device 49 are included in seriatim. More particularly, the joining device comprises a linkage composed of the thermostat 44 provided with a stem 46, a bell crank 47 pivoted thereto and fulcrumed on a stationary bracket 48, and a pressure gauge 49 compressible by atmospheric pressure, such pressure gauge being connected by a stem 50 to the bell crank 47 and by a stem 51 to the pin or follower member 22. The other elements are arranged in the same manner as shown in Figs. 1, 2 and 3 and described with reference thereto.

Hence, it will appear that in this embodiment the linkage only for adjusting the elevation of the follower member 22 differs from the mechanism shown in Figs. 1, 2, and 3; the thermostat 44 and the pressure gauge 49 being mounted in tandem so as to act jointly on the stem 51. Preferably, the pivotal connection between the bell crank 47 and the stem 50 is axially aligned with the pivot pin 39 pivotally connecting the link member 37 to the bracket 38, as will appear from Fig. 5.

In the embodiment shown in Figs. 6 and 7, the joining device which transfers the actuating motion from the diaphragm 16 to the control rod 12 comprises:

(1) a first link 52 mounted for rocking motion about an axis 53 which is laterally offset from the first direction, i. e. the axis of rod 12;

(2) a second link 54 pivotally connected to the first link 52 at a pivot point 55, and

(3) means for connecting one of said links, such as 54, to the control member 12 and for connecting the other one of said links, such as 52, to the main actuating member or diaphragm 16, such means comprising links 56 and 57 in the embodiment shown.

The pivot point 55 is so spaced from the axis 53 that it is substantially aligned with said first direction, i. e. the axis of control member 12, as indicated at 55', when the throttle is closed and the diaphragm is fully sucked into the housing 15 for zero fuel injection, such position of the links 52, 54 and 57 being indicated by the dash-dotted lines 52', 54' and 57'. The two-armed lever 27 which is mounted and operated in the same manner as described with reference to Figs. 1, 2 and 3 by a thermostat 26, a pressure gauge 25, and associated levers 28 and 33 and links 31 and 32, is directly or indirectly connected to the second link 54, for instance by a connecting pin 59, so as to rock link 54 about the pivot point 55. Such rocking motion is indicated by the arrows 58 when the parts assume the position shown in full lines, and by the arrows 60 when the parts assume the position indicated by the dash-dotted lines 52', 54' and 57'. Here again, a certain increment of the adjusting motion produced by the correction member 25 or 26 will cause a corrective adjustment of control member 12, such corrective adjustment, however, decreasing down to zero when the elements move from the position shown in full lines to the position shown in dash-dotted lines. When the quantity of fuel injected has been reduced to zero, the pin 59 moves substantially at right angles to the primary direction of motion produced by the diaphragm 16 so that such up-and-down adjustment has practically no influence upon the position of the control rod 12.

From the above description it will be understood that the control member 12 adjusting the fuel feed is actuated by a substantially straight linkage movable in its lengthwise direction, such linkage being automatically actuated by an actuating member, such as diaphragm 16, responsive to any change of the weight of the air charge of the engine. One or more correction members movable in response to a physical change in the atmosphere, such as change in temperature or pressure, are adapted to adjust a joining device included in the linkage. The adjusting motion so produced, however, is variable by movement of the actuating member 16 in such a manner that, for a given movement of the correction member 25 or 26, positioning the control member 12 for a larger fuel feed causes the corrective adjustment to be larger than positioning the control member 12 for a small fuel feed, as shown at 23'. The corrective effect produced by the correction member 25 or 26 on the position of control member 12 is proportional to the weight of the air charge. Therefore, when the engine is operated with half of its full power, the control member 12 determining the amount of fuel injected is only adjusted half of the full adjustment obtained by the same change of the atmospheric condition when the engine is operated at full power. When the fuel feed is reduced to zero, no adjustment of control member 12 will be produced by a change of the atmospheric condition. Such a correction proportional to the total quantity of fuel injected corresponds to the exact requirements.

In one form of the novel control system, the joining device mounted for an adjusting motion transversely to the main actuating motion comprises a slotted member rockable about a fixed pivot point and a follower or pin movable in the slotted member, the rocking motion of

the slotted member being produced by the main actuating motion in such a sense that the slot of the slotted member will be more inclined when the control member is in its full power position and will be less inclined when the control member is in a reduced power position. The maximum inclination of the slot, however, is so small that the actuating force transferred by the joining device will not produce any material force component reacting upon the thermostat or pressure gauge.

In another form of the novel control system, the joining device capable of adjustment transversely to the main actuating motion comprises a pair of links pivoted to each other. The corrective effect is obtained in that one of the links is movable about a pivot point which, when the linkage is actuated to increase the fuel feed, is increasingly offset from the direction of the main actuating motion.

The term "physical change in the atmosphere" is used hereinafter to designate changes occurring in the atmosphere due to variations in temperature, pressure, et cetera.

While I have described my invention with reference to a number of preferred embodiments thereof, I wish it to be clearly understood that the same is in no way limited to the details described, but is capable of numerous modifications within the scope of the appended claims.

What I claim is:

1. In a governing system for a fuel feed device of an internal combustion engine, the combination comprising a control member movable in a first direction to vary the quantity of the fuel fed to the engine, a main actuating member responsive to any change of the weight of combustion air fed into the internal combustion engine, a joining device connecting said members for transferring the actuating motion from said actuating member to said control member in said first direction, a correction member movable in response to a physical change in the atmosphere, and means connecting said correction member to said joining device for transferring an adjusting motion from said correction member to said joining device in a second direction extending transversely to said first direction to thereby effect a corrective adjustment of said control member in such direction said joining device including link means extending substantially transversely to said first direction and being pivotally mounted about an axis spaced from the main direction of the joining device and being angularly displaceable by the movement of said actuating member, said angular displacement of said joining device together with said actuating motion rendering said corrective adjustment in said first direction variable, so that for a given movement of said correction member and with said control member in a position for large fuel feed, said corrective adjustment is larger than when the control member is positioned for a smaller fuel feed.

2. In a governing system for a fuel-injecting device of an internal combustion engine, the combination comprising a control member movable in a first direction to vary the quantity of the fuel injected, a diaphragm, means for subjecting said diaphragm to the vacuum prevailing in the intake manifold of the engine, a joining device connecting said diaphragm to said member for transferring the actuating motion from said diaphragm to said control member in said first direction, a correction member movable in response to a physical change in the atmosphere, and means connecting said correction member to said joining device for transferring an adjusting motion from said correction member to said joining device in a second direction extending transversely to said first direction to thereby effect a corrective adjustment of said control member in said first direction in addition to said actuating motion said joining device including link means extending substantially transversely to said first direction and being pivotally mounted about an axis spaced from the main direction of the joining device

and being angularly displaceable by the movement of said diaphragm, said angular displacement of said joining device together with said actuating motion rendering said corrective adjustment in said first direction variable, so that for a given movement of said correction member and with said control member in a position for large fuel feed, said corrective adjustment is larger than when the control member is positioned for a smaller fuel feed.

3. The combination claimed in claim 1 in which said joining device comprises a cam mounted for bodily movement in said first direction, a follower, and means for holding said follower in engagement with the cam face of said cam, said follower being connected to one of said members and said cam being connected to the other one of said members for said transfer of actuating motion, means being provided for angularly displacing said cam in response to said actuating motion, said cam face extending substantially perpendicularly to said first direction when said control member is positioned for zero fuel feed, said correction member being connected to said cam mechanism for causing relative displacement of said cam and said follower along said cam face.

4. In a governing system for a fuel-injecting device of an internal combustion engine, the combination comprising a control rod movable substantially lengthwise to vary the quantity of the fuel injected, a diaphragm, means for subjecting the diaphragm to the vacuum prevailing in the intake manifold of the engine, a link element provided with a slot and extending substantially transversely to said rod and being pivotally mounted for angular displacement about an axis spaced from said rod, said slot extending substantially perpendicularly to said control rod when the latter is in its zero fuel feed position, a follower element movably guided in said slot, one of said elements being connected to said rod and the other one of said elements being connected to said diaphragm for transfer of an actuating motion from said diaphragm to said control rod, a correction member movable in response to a physical change in the atmosphere, and means connecting said correction member to one of said elements for relative displacement of said elements along said slot.

5. The combination claimed in claim 1 in which said joining device comprises a first link mounted for rocking motion about an axis laterally offset from said first direction, a second link pivotally connected to said first link at a pivot point, and means for connecting one of said links to said control member and for connecting the other one of said links to said main actuating member, said means connecting said correction member to said joining device comprising link members connecting said correction member to said second link for rocking the same about said pivot point, said pivot point being substantially aligned with said first direction when said main actuating member is set for zero fuel feed.

6. The combination claimed in claim 1 in which said means connecting said correction member to said joining device comprises a two-armed lever, a correction member being linked to each arm of said lever.

7. The combination claimed in claim 1 in which said means connecting said correction member to said joining device for transfer of an adjusting motion from said correction member to said joining device in a second direction comprises a two-armed lever and a pair of links extending substantially parallel to each other and to said second direction, each of said links being pivotally connected to one of said arms, a correction member movable in response to a change of atmospheric temperature being connected to one of said links, and a correction member movable in response to the temperature of the atmosphere being connected to the other one of said links.

8. In a governing system for a fuel-injecting device of an internal combustion engine, the combination comprising a control rod movable substantially lengthwise to vary the quantity of the fuel injected, a diaphragm, means

for subjecting the diaphragm to the vacuum prevailing in the intake manifold of the engine, a link element provided with a slot and extending substantially transversely to said rod and being pivotally mounted for a rocking motion about an axis spaced from said rod, a follower element movably guided in said slot, one of said elements being connected to said rod and the other one of said elements being connected to said diaphragm for transfer of an actuating motion from said diaphragm to said control rod, said axis being located for said slot to extend substantially perpendicularly to said control rod when said vacuum reaches a maximum causing said diaphragm to set control rod to the zero fuel-injecting position, a pair of links extending parallel to each other and to said link element and having a length substantially equal to that of said link element, a two-armed lever connecting said links and carrying said follower element, a thermostat connected to one of said links for lengthwise adjustment thereof in response to a change of the atmospheric temperature, and a device responsive to atmospheric pressure connected to the other one of said links for lengthwise adjustment thereof, whereby said follower element will be moved in said slot in response to variations of the atmospheric temperature and of the atmospheric pressure.

9. The combination claimed in claim 1 in which said means connecting said correction member to said joining device comprises a lever and link arrangement including another correction member movable in response to a physical change in the atmosphere different from said first-mentioned physical change, one of said correction members being arranged at one end of said lever and link arrangement, while the other one of said correction members forms part of said link arrangement, the action of said two correction members being in series.

10. The combination claimed in claim 1 in which said means connecting said correction member to said joining device comprises a lever and link arrangement composed of a thermostat, a lever pivoted thereto, an element compressible by atmospheric pressure connected to said lever, and means connecting said compressible element to said joining device.

11. In a governing system for a fuel feed device of an internal combustion engine, the combination comprising a control member movable in a first direction to vary the quantity of the fuel feed to the engine, a main actuating member responsive to any change of the weight of combustion air fed into the internal combustion engine, a joining device connecting said members for transferring the actuating motion from said actuating member to said control member in said first direction, a correction member movable in response to a physical change in the atmosphere, and means for connecting said correction member to said joining device for transferring an adjusting motion from said correction member to said joining device in a second direction extending transversely to said first direction to thereby effect a corrective adjustment of said control member in said first direction in addition to said actuating motion, said joining device including a link element connected with said main actuating member and extending substantially transversely to said first direction and being pivotally mounted for rocking motion about an axis spaced from the main direction of the joining device, said adjusting motion being variable corresponding to the location of said link element, whereby positioning said joining device for a large fuel feed causes said corrective adjustment to be larger than positioning said joining device for a smaller fuel feed.

12. In a governing system for a fuel feed device of an internal combustion engine, the combination comprising a control member movable in a first direction to vary the quantity of the fuel feed to the engine, a main actuating member responsive to any change of the weight of combustion air fed into the internal combustion engine, a joining device connecting said members for transferring

the actuating motion from said actuating member to said control member in said first direction, said joining device moving substantially rectilinearly between said actuating member and said control member, a correction member movable in response to a physical change in the atmosphere, and means for connecting said correction member to said joining device for transferring an adjusting motion from said correction member to said joining device in a second direction extending transversely to said first direction to thereby effect a corrective adjustment of said control member in said first direction in addition to said actuating motion, said joining device including a link element connected with said main actuating member and extending substantially transversely to said first direction and being pivotally mounted for rocking motion about an axis spaced from the main direction of the joining device, said adjusting motion being variable corresponding to the location of said link element, whereby positioning said joining device for a large fuel feed causes said corrective adjustment to be larger than positioning said joining device for a smaller fuel feed.

13. In a governing system for a fuel-injecting device of an internal combustion engine, the combination comprising a control member movable in a first direction to vary the quantity of the fuel injected, a diaphragm, means for subjecting said diaphragm to the vacuum prevailing in the intake manifold of the engine, a joining device connecting said diaphragm to said member for transferring the actuating motion from said diaphragm to said control member in said first direction, a correction member movable in response to a physical change in the atmosphere, and means connecting said correction member to said joining device for transferring an adjusting motion from said correction member to said joining device in a second direction extending transversely to said first direction to thereby effect a corrective adjustment of said control member in said first direction in addition to said actuating motion, said joining device including a link element extending substantially transversely to said first direction and being pivotally mounted for rocking motion about an axis spaced from the main direction of said joining device, said adjusting motion being variable depending on the location of said link element, whereby positioning said joining device for a large fuel feed causes said corrective adjustment to be larger than positioning said joining device for a smaller fuel feed.

14. In a governing system for a fuel feed device of an internal combustion engine, the combination comprising a control member movable in a first direction to vary the quantity of fuel fed to the engine, means responsive to any change in the weight of the combustion air fed to said internal combustion engine, and means for connecting said first-mentioned means to said control member including means responsive to a physical change of the atmosphere for further adjusting said control member in said first direction and for simultaneously therewith varying the proportional control influence of said last-named means on said control member dependent on the position of said first-named means, said proportional control influence being such that for a given movement of said last-named means and with said control member in a position for large fuel feed, said further adjustment of said control member is larger than when the control member is positioned for a smaller fuel feed.

15. In a governing system for a fuel feed device of an internal combustion engine, the combination comprising a control member movable in a first direction to vary the quantity of fuel fed to the engine, means responsive to any change in the weight of the combustion air fed to said internal combustion engine, and means for connecting

said first-mentioned means to said control member including means disposed approximately at right angle to said connecting means and responsive to a physical change of the ambient air for further adjusting said control member in said first direction and for simultaneously therewith varying the proportional control influence of said last-named means on said control member, dependent on the adjustment thereof by said first-mentioned means, said proportional control influence being such, that for a given movement of said last-named means and with said control member in a position for large fuel feed, said further adjustment of said control member is larger than when the control member is positioned for a smaller fuel feed.

16. In a governing system for a fuel feed device of an internal combustion engine, the combination comprising a control member movable in a first direction to vary the quantity of fuel fed to the engine, means responsive to any change in the weight of the combustion air fed to said internal combustion engine, and means for connecting said first-mentioned means to said control member in a first essentially rectilinear direction including means disposed in a second direction responsive to a physical change of the ambient air for further adjusting said control member in said first direction and for simultaneously therewith varying the proportional control influence of said last-named means on said control member dependent on the position of said first-mentioned means, said first and second direction being disposed essentially transversely to each other, said proportional control influence being such that, for a given movement of said last-named means and with said control member in a position for large fuel feed, said further adjustment of said control member is larger than when the control member is positioned for a smaller fuel feed.

17. In a governing system for a fuel feed device of an internal combustion engine, the combination comprising a control member movable in a first direction to vary the quantity of fuel fed to the engine, means responsive to any change in the weight of the combustion air fed to said internal combustion engine, means for connecting said first-mentioned means to said control member in a first essentially rectilinear direction, link means movable essentially transversely to said first direction and responsive to a physical change in the ambient air, and pivotal means connecting said link means with said connecting means further adjusting said control member in said first direction and for simultaneously therewith varying the proportional control influence of said link means on said control member dependent on the instantaneous position of said first-mentioned means, said pivotal means being movable over a limited distance approximately parallel to said second direction relative to said connecting means, said proportional control influence being such that, for a given movement of said link means and with said control member in a position for large fuel feed, said further adjustment of said control member is larger than when the control member is positioned for a smaller fuel feed.
